UNITED STATES PATENT OFFICE.

JAMES GUNNELL MALONE AND JOHN A. DORMER, OF DETROIT, MICHIGAN.

ROCK OR ORE CRUSHING MACHINE.

Application filed October 16, 1925, Serial No. 62,692. Renewed November 12, 1926.

This invention relates to a rock or ore crushing machine and has special reference to that type of crusher wherein the material to be crushed is deposited in a crushing chamber containing an oscillatory crushing head by which the material is crushed against a stationary wall of the chamber. In this type of crusher the material feeds by gravity or by head pressure so that the material is wedged between the walls of the crushing chamber and disintegrated by the movable wall of the chamber squeezing the material against the stationary wall of the chamber. The crushing pressure or strains may be said to be in radial directions, and we have devised a novel operating mechanism by which a crushing head is moved in an oscillatory manner relative to a chamber wall, thus producing strains which more thoroughly disintegrate the material. Again, the head constitutes an agitator within the crushing chamber so that the material cannot arch therein or fail to rapidly feed through the crushing chamber. By agitating the material within the chamber, through the medium of the oscillatory crusher head pockets are temporarily formed into which the material may fall and become wedged between the walls of the crushing chamber to the extent of being positively crushed as the head is shifted.

In addition to the oscillatory crushing head and the operating mechanism therefor, our machine possesses other advantages, some of which are as follows:—first, the compact arrangement of the driving mechanism relative to the crushing head provides a machine of less height than the usual practice; second, permits of greater access being had to the interior of the machine when parts are to be renewed; third, affords a bottom discharge and eliminates considerable installation heretofore required for a side discharging machine; fourth, permits of the crushing head being readily adjusted to compensate for wear in connection with the operating mechanism, and fifth, includes a construction that is more durable and efficient for rock or ore crushing purposes.

Numerous other advantages are gained by our construction which will now be described in detail by aid of the drawings, wherein—

Figure 1 is a vertical sectional view of the crushing machine;

Fig. 2 is a horizontal sectional view of the operating mechanism of the machine taken

on the line II—II of Fig. 1 and on a smaller scale;

Fig. 3 is a similar view taken on the line III—III of Fig. 1, but on a larger scale;

Fig. 4 is a vertical cross sectional view of the lower portion of the machine illustrating a modified form of operating mechanism, and

Fig. 5 is a horizontal sectional view taken on the line V—V of Fig. 1, but on a smaller scale.

Reference will first be had to all the figures, except Fig. 4 and the reference numeral 1 denotes a suitable foundation or support on which the machine may be mounted for a bottom discharge. On the foundation or support 1 is a bottom shell 2 and seated on and in this shell is a frusto-conical shaped top shell 3 which is secured to the bottom shell by nut equipped bolts 4 or other fastening means.

Seated on and in the top shell 3 is a hopper 5 secured to the top shell by nut equipped bolts 6 or other fastening means.

The top shell 3 is provided with a durable liner 7 interengaging the top shell and resting on the bottom shell with the liners of such configuration as to provide a crushing chamber 8 having an annular wall that tapers outwardly from the upper end of the chamber to a point in proximity to the bottom of the chamber, where the angularity of the taper is increased for the outlet of crushed material into the bottom shell and a bottom discharge therefrom. The liner 7 is made of more durable material than the top shell and may be made in sections or parts removable from the top shell so that a new liner can be easily placed therein.

The bottom shell 2 has a spider 9 supporting a substantially cylindrical housing 10 provided with a central support 11 for bearing plates 12 which are slideable on the support 11. These bearing plates support a nut or screw 13 adjustable in the lower hub portion 14 of a frusto-conical shaped crushing head 15 having an upper hub portion 16 extending into a housing 17 carried by a hopper spider 18. The spider housing 17 contains an indurate liner 19 against which bears the lower annular edge of a conical bushing 20 mounted on the upper end of the hub portion 16 of the crushing head. The housing opening 21 for the hub portion 16 is large enough for the wobbling movement of the hub portion 16 in the hous-

ing, and a dust cap or deflector 22 is mounted on the housing to prevent rock or ore from interfering with any oscillatory movement of the hub portion 16 within the spider housing 17.

The hub portion 16 is coaxially of the hub portion 14. Extending through the hub portion 16, the head 15 and into the nut or screw 13 is a rod 23 having tangs or end shanks so that a wrench or suitable instrument on the upper end of the rod 23 will permit of it being rotated to impart rotation to the nut or screw 13 and thus raise or lower the crushing head 15 relative to the 15 spider housings 10 and 17.

Mounted on the lower hub portion 14 of the crushing head is a bushing 24 and mounted on this bushing is an inner frustro-conical shaped race member 25 which has its 20 outer wall undulating, as best shown in Fig. 3, to provide a plurality of protuberances or cam surfaces 26. Attached to the lower end of the inner race member 25 is a bearing ring 27 on a wear plate 28 supported by the 25 housing 10. This bearing ring is the equivalent of a plurality of brackets for supporting the inner race member 25 so that the lower hub portion 14 of the crushing head may be adjusted in the inner race member. 30 The bearing ring 27 supports the inner race member so that it may be laterally shifted when an oscillatory motion is imparted to the crushing head.

Mounted in the upper end of the housing 35 10 and retained therein by a clamping ring 29 is an outer race member 30 presenting an annular wall to the undulating wall of the inner race member 25, and between the race members 25 and 30 are a series of equally 40 spaced conical rollers 31 arranged in a cage 32 mounted on a ledge or support 33 within the lower housing 10. The rollers 31 constantly contact with the race members 25 and 30 and to compensate for wear various 45 kinds of shims, washers, wear plates and such mechanical expedients may be used.

In the lower part of the housing 10 is a rotatable worm wheel 34 provided with a pin 35 extending into a lateral fork 36 fixed 50 on the bearing ring 27, thus establishing a driving relation between the worm wheel 34 and the inner race member 25. The housing 10 has suitable bearing portions for a worm 37 meshing with a worm wheel 34 and 55 adapted to be driven from a suitable source of power.

The crushing head 15 has a depending annular skirt 38 surrounding the upper end of the housing 10 and between the skirt and 60 said housing may be a conventional form of dust guard 39. Such guards or like devices are used wherever necessary to prevent dust or foreign matter from interfering with the operation of the driving mechanism for the 65 crusher.

Mounted on the crushing head 15 are interchangeable and renewable concaves 40 retained thereon by suitable clips 41 or other fastening means. These concaves confront the liner 7 of the crushing chamber 8 and 70 it is between the walls of the crushing chamber that material from the hopper 5 is subjected to a crushing action brought about by the oscillatory movement of the crushing head relative to the outer wall of the crushing chamber.

In operation the inner race member 25 causes a gyratory movement to be imparted to the lower part of the crushing head and such movement is permissible because the 80 bearing ring 27 and bearing plates 12 are shiftable relative to the housing 10, while the upper hub portion 16 of the crushing head is supported for a wobbling movement within the bearing provided by the spider 85 housing 17. The gyratory movement imparted to the crushing head 15 causes it to constantly shift in an eccentric relation to the outer wall of the crushing chamber with resultant radial and tangential strains 90 against material between the walls of the crushing chamber. This will insure greater and more rapid disintegration of the material which is conveniently discharged through the bottom shell of the machine. 95

In lieu of the conical anti-frictional rollers 31 between the race members 25 and 29 of the crusher, we may use straight rollers 42 as shown in Fig. 4. We may also substitute a horizontal beveled gear wheel 43 and 100 a driven beveled gear wheel 44 for the worm and worm wheel previously described. A bearing ring 45 may form part of the inner race member 46 and have a pin and slot connection with the horizontal gear wheel 43 to accomplish the same gyratory actuation 105 of the crushing head as previously described. We may also suitably support a crushing head 47 from overhead and provide a supporting core 48 of said head with a ball and 110 socket connection 49 in the inner race member 46. The ball and socket connection 49 will constitute a universal connection between the crushing head and its operating mechanism, so that the driven inner race 115 member 46 may impart a gyratory motion to the crushing head. The universal joint also permits of the crushing head 47 being readily adjusted when occasion requires, and we do not care to confine our invention to any 120 particular supporting or suspension means for the head 47, as our invention is particularly directed to the operating or actuating mechanism by which the gyratory motion is imparted to the crushing head. Furthermore, it is to be understood that the construction and arrangement of parts are susceptible to such variations and modifications as fall within the scope of the appended 125 claims.

What we claim is:—

1. In a rock or ore crushing machine having a crushing chamber with a driven crushing head therein:—driving means for said crushing head, said means being located below said head and adapted to impart a gyroscopic motion thereto, said driving means including inner and outer race members with rollers therebetween and one of said race members provided with an undulating surface.
2. In a rock or ore crushing machine, a crushing chamber, a crushing head therein provided with a hub portion, a stationary outer race member, a shifttable inner race member into which extends the hub portion of said crushing head, rollers between said race members, one of said race members having an irregular surface to cause said crushing head to laterally shift in said crushing chamber, and driving means for the last mentioned race member.
3. A crushing machine as called for in claim 2, further characterized by adjusting means in the hub portion of said crushing head adapted for either raising or lowering said head relative to said race members.
4. A crushing machine comprising a crushing chamber, a crushing head therein having its upper end held so that its lower end may be laterally shifted in said chamber, and means adapted to impart a gyroscopic movement to said crushing head, said means including a driven undulating member into which extends a portion of said head.
5. A crushing machine comprising a
- crushing chamber, a crushing head therein having its upper end held so that its lower end may be laterally shifted in said chamber, and means adapted to impart a gyroscopic movement to said crushing head, said means including a shifttable roller bearing for the lower portion of said head with said bearing having a stationary portion and another portion driven relative to said stationary portion.
6. A crushing machine including a chamber adapted to receive material to be crushed, a head in said chamber supported to be wobbled therein, and driving means adapted to impart a wobbling movement to said head, said driving means including roller race members with one of said race members of undulating configuration.
7. A crushing machine including a chamber adapted to receive material to be crushed, a head in said chamber supported to be wobbled therein, a driving means adapted to impart a wobbling movement to said head, said driving means including a driven gear wheel, and a shifttable head moving bearing ring having a pin and slot connection with said gear wheel.
8. A means for transmitting a gyroscopic movement to a crusher shaft, comprising a cam carried on the end of said shaft, tapered rollers on which said cam bears, and an outer stationary race for the rollers.

In testimony whereof we affix our signatures.

JAMES GUNNELL MALONE.
JOHN A. DORMER.
